UNITED STATES PATENT OFFICE.

ALFRED C. GILBERT, OF NEW HAVEN, CONNECTICUT, ASSIGNOR TO THE A. C. GILBERT COMPANY, OF NEW HAVEN, CONNECTICUT, A CORPORATION OF CONNECTICUT.

RHEOSTAT.

Application filed January 28, 1918. Serial No. 214,141.

To all whom it may concern:

Be it known that I, ALFRED C. GILBERT, a citizen of the United States, residing in the city and county of New Haven and State 5 of Connecticut, have invented certain new and useful Improvements in Rheostats, of which the following is a full, clear, and exact description.

This invention relates to rheostats, and it 10 has particular reference to a small, cheap rheostat construction primarily designed for use in the hollow base portion of an electric fan, although my improvements are applicable to other apparatus where simple and 15 economical means for controlling the speed of a motor or the like are required.

The primary object is to furnish an efficient and reliable rheostat which can be produced at minimum expense.

20 Another object is to provide improved means for mounting the rheostat on a suitable base plate, which may be the plate that encloses the open bottom portion of a fan base.

25 To these and other ends, the invention consists in the novel features and combinations of parts to be hereinafter described and claimed.

In the accompanying drawing:

30 Fig. 1 is a side elevation of a fan base, having a rheostat embodying my improvements;

Fig. 2 is a bottom view of the fan base;

35 Fig. 3 is a side elevation of the rheostat and its base plate, the hollow casting or standard of the fan being indicated in dotted lines;

Fig. 4 is a side elevation of the rheostat, taken at right angles to Fig. 3;

40 Fig. 5 is a top plan view of the parts shown in Fig. 4, showing the controlling lever in the position in which the flow of current is interrupted;

Fig. 6 is a vertical central section of the 45 rheostat;

Fig. 6^A is a section of certain parts shown in Fig. 6 on a larger scale;

Fig. 7 is a horizontal section taken beneath the insulating plate or platform, on which 50 the contacts are mounted, looking upward;

Fig. 8 is a diagram of the electrical connections; and

Figs. 9 and 10 are top and bottom views respectively of the controlling lever.

In the drawings, my improvements are 55 illustrated as applied to a base for a small electric fan, which base is indicated generally by reference character A, and comprises usually a hollow standard 11 of cast metal having a lower open end which is 60 closed by a sheet metal plate 12 secured thereto by screws 13. The plate 12 is used as a base plate for a rheostat designated generally by reference character B, which rheostat is housed in the hollow bottom 65 portion of the fan standard or base and carried by and removable with the base plate. The rheostat B embodies in its construction a controlling lever 14, projecting laterally through a slot 15' at one side of 70 the hollow member 11. In the particular example shown, this lever has three main positions, one corresponding to the total interruption of the current, a second corresponding to a half speed operation of the 75 fan, and a third corresponding to a full speed operation thereof.

The rheostat comprises in its construction an insulating plate or platform 15, which may advantageously consist of a fibrous insulating material, and, in the example shown, this plate serves as a mounting for the controlling lever 14 and for two fixed contacts 16, 17, cooperating therewith. The plate 15 is supported by integral lugs 18, 85 struck-up out of the sheet metal plate 12 and having reduced upper extremities 18' which pass through slots in the insulating plate, said extremities 18' being thereafter twisted out of the planes of the main portions of the 90 lugs, as shown more particularly in Fig. 5, so that the insulating plate is firmly clinched on top of shoulders at the upper portions of the lugs. The pivot of the controlling lever 14 is located intermediate and substantially in line with the lugs 18, and it preferably comprises a member 19 in the form of a bolt having a head 20 disposed beneath the insulating platform, the shank of said bolt passing through an opening in the platform to a considerable height above the latter, as shown in Fig. 6. Between the bolt head 20 and the under surface of the insulating platform is a washer 21, and a similar washer 22 is interposed between the upper surface of the platform and the under surface of the controlling lever 14. The pivot bolt passes through the controlling 100 105 110 115 120 125 130 135 140 145 150 155 160 165 170 175 180 185 190 195 200 205 210 215 220 225 230 235 240 245 250 255 260 265 270 275 280 285 lever at a point intermediate of its ends, for which purpose said lever is provided with a suitable opening, said opening, in the example shown, being located somewhat nearer 5 the contact end (cooperating with contacts 16, 17) than the operating end projecting out of the slot 15. On top of the controlling lever, another washer 23 embraces the bolt and on top of this washer is a nut 24, by 10 which all the parts are firmly held in place, so as to provide a mounting for the controlling lever which is neither too tight nor too loose. Preferably, the nut 24 will be melted after the parts are assembled, so that 15 it cannot be displaced on the bolt, whereby the proper adjustment of the lever relatively to its support will be maintained.

In addition to the function of pivoting or swiveling the controlling lever, the bolt 19 20 serves to carry the current, as hereinafter pointed out, and it likewise serves as a mounting for the resistance element, which is preferably constituted by a sleeve 25 of some suitable resistance material having a 25 vitreous coating, said sleeve having outwardly extending wire connections at the upper and lower parts thereof, so that a reduced flow of current will pass through it when the respective connections are connected with opposite poles of a source of current. However, while it is advantageous to 30 use a resistance element of ceramic material in the form of a sleeve, I do not limit myself in this respect. In the form shown, 35 the resistance sleeve, which is suitably insulated by its covering or coating, is supported by the connecting wires, which are rather stiff, and the bolt 19 merely serves to center it. One connecting wire 26 extends 40 from the contact 16 to one end of the sleeve and is suitably connected to it (in this case the upper end, as shown in Fig. 3), while another wire 27 extends from the contact 17 to the other (lower) end of the sleeve, 45 to which it is suitably connected. The contacts 16, 17 may advantageously consist of headed fasteners of well-known type, having their heads disposed on the upper surface of platform 15 and provided with bendable 50 shanks 16^a, 17^a extending through openings in the platform and clinched over on the under surface of the latter. In the particular example shown, the wires 26, 27 are soldered to the ends of the flexible contact 55 shanks, which are bent up over the edge of the platform, as shown in Fig. 4. The shank of each contact is made in two parts that can be separated from each other, as in the ordinary McGill fastener.

60 The electrical connections are as follows: One wire 28 coming in from the battery, or other current source, passes through an insulating nipple 29 in the side wall of member A and passes upward in said member to 65 the motor (not shown) mounted on top of

the same. From the motor, a return wire 30 comes down into the hollow base member through the open upper end thereof, and is connected, as by soldering, with the upper end of the bolt 19, as shown at 31 in Fig. 3. 70 A return wire to the battery, or other current source, is connected to the shank of contact 17, said wire being designated by reference character 32, and passes out of the hollow base through the nipple 29. 75

It will be observed that the lug ends 18' are so located as to constitute stops for limiting the swinging movement of the controlling lever in opposite directions (Fig. 5). This is a factor of some importance in facilitating the assemblage of the parts and the testing of the rheostat unit before it is placed in the fan base. When the rheostat has been placed in the base, however, the end portions of the slot 15' properly limit the movement of the lever. This lever is preferably of composite construction, having a main portion 14' of fibrous material and a metal contact portion 14'', preferably of brass. The metallic portion 14'' extends 90 somewhat beyond the pivot of the lever and is in full contact with the metal washers above and below the lever, which, in turn, contact with the bolt shank so that the current will pass properly from the bolt to the 95 movable contact 14'' or vice versa. The operation of the device will be more or less obvious from the foregoing description. Assuming that the lever is in the position shown in Fig. 5, the flow of current is entirely interrupted, owing to the fact that there is no connection between the wires 28, 32. When the lever is moved so that its contact portion 14'' is in contact with the head of contact 16, the current, it can be assumed, 100 passes into the motor by wire 28, out of the motor by wire 30 and bolt 19 to contact 14'', into contact 16, thence through the resistance 25 by wires 26 and 27 to contact 17, and thence to the current source by wire 32. As 105 the current passes through the resistance element, the speed of the fan or other device is cut down to an extent corresponding to the amount of resistance interposed. When the lever is moved so that its contact portion 110 14'' is in contact with the head of contact 17, the current is shunted about the resistance in an obvious manner and the motor 115 operates at full speed.

In practice, the various wires or leads 120 should be properly enclosed and insulated to prevent short circuiting, as will be obvious.

The particular manner of fastening the contact portion 14'' to the fibrous body portion 14' of the controlling lever is shown in Fig. 9. In this example, the metal plate overlaps the fibrous plate and is provided with struck-up lugs 14^a, passing through and riveted in perforations of the fibrous part. 125 130

The opening 14^b for the pivot bolt is formed partly in the metal part and partly in the fibrous part.

Fig. 8 shows a simple diagram of the electrical connections, including the motor, which is designated by M, the resistance 25, the fixed contacts 16 and 17, and the movable contact 14".

Various changes may be made in the details without departing from the scope of the invention as defined in the claims.

What I claim is:

1. In a device such as described, a sheet metal plate having struck-up lugs, a platform supported on said lugs, and a rheostat structure on the platform.
2. In a device such as described, a sheet metal base plate having struck-up lugs, a platform of insulating material supported on said lugs, and a rheostat structure mounted on said platform.
3. In a device such as described, a sheet metal base plate having struck-up lugs, a platform of insulating material supported on said lugs, and a rheostat structure mounted on said platform, including at least two fixed contacts on the platform and a movable contact to cooperate successively with said fixed contacts.
4. In a device such as described, a base plate, a platform of insulating material spaced above the same but carried thereby, a bolt passing through an opening in the platform, a controlling lever of insulating material pivoted to the platform by means of said bolt, a conductor strip secured to a face of said lever, and a fixed contact cooperating with said conductor strip.
5. In a rheostat, a base plate, a platform of insulating material spaced above the same but supported thereby, two fixed contacts on said platform, a resistance element connected with said contacts, a controlling lever formed of insulating material pivotally mounted upon said platform, and a contact strip secured to said lever and movable thereby to electrically connect either of said fixed contacts with said pivot.
6. In a rheostat, a plate of insulating material, fixed contacts on said plate, a resistance element connected with said contacts, a controlling lever formed of insulating material and pivotally mounted upon said plate, and a contact strip secured to a face of said

lever and movable thereby to electrically connect any one of said fixed contacts to said pivot.

7. In a rheostat, a plate of insulating material, fixed contacts on said plate, a resistance element connected with certain of said contacts, a controlling lever pivoted on said plate and common means to pivot said controlling lever and support said resistance element on said plate.

8. In a rheostat, a supporting plate or platform, a pair of fixed contacts supported thereon, a lever pivotally mounted thereon and having a contact member cooperating with said fixed contacts, a resistance element in circuit between said contacts and mounted above said lever and common means for pivoting said lever, centering said resistance element and forming an electrical connection with said contact member.

9. In a rheostat, an insulating plate, a pair of fixed contacts carried thereby, a pivotally mounted movable contact cooperating with the fixed contacts, and a resistance element bridging said fixed contacts and mounted above the pivot point of said movable contact about an electrical terminal of said rheostat connected with said movable contact.

10. In a rheostat, a base, a switch lever pivotally mounted thereon, a resistance element, adapted to be controlled by said lever, said lever being mounted between said base and said resistance element and common means for pivoting said lever and retaining said resistance element.

11. A rheostat comprising an insulating base having fixed contacts thereon, a resistance element bridging said contacts, a pivoted handle carrying a contact member cooperating with said fixed contacts and means to electrically connect said contact member with a terminal of said rheostat and to retain said resistance element upon said base.

12. In a rheostat, a base, a switch lever pivotally mounted thereon, and a resistance element adapted to be controlled by said lever, said resistance element being mounted above said base and said lever upon the terminals leading thereto and positioned thereon by a terminal connected with said lever.

In witness whereof, I have hereunto set my hand on the 21st day of January, 1918.

ALFRED C. GILBERT.
